The ornamental design for a note pad holder, as shown and described.

DESCRIPTION

FIG. 1 is a top, left front isometric view of a note pad holder showing our new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a left side elevational view thereof, the right side elevational view being the mirror image thereof.
